UNITED STATES PATENT OFFICE.

EDWARD STEWART, OF MINNEAPOLIS, MINNESOTA.

SILO.

1,360,461.

Specification of Letters Patent. Patented Nov. 30, 1920.

Application filed March 30, 1920. Serial No. 370,039.

To all whom it may concern:

Be it known that I, EDWARD STEWART, a citizen of the United States, and a resident of Minneapolis, in the county of Hennepin and State of Minnesota, have invented a certain new and useful Silo, of which the following is a specification.

The object of my invention is to provide a silo structure of wooden boards or strips so constructed and connected together in the silo as to make a strong rigid construction with the strips arranged horizontally and so connected and having such co-acting parts as to prevent the discharge of moisture inwardly or outwardly through the silo wall.

A further object is to provide such a silo structure having parts which may be made of standard sizes and shapes in lefts and rights and so connected together as to accomplish the objects above mentioned.

With these and other objects in view my invention consists in the construction, arrangement and combination of the various parts of the device, whereby the objects contemplated are attained, as hereinafter more fully set forth, pointed out in my claim and illustrated in the accompanying drawings, in which:

Figure 1 shows a front elevation of a silo embodying my invention.

Fig. 2 shows a vertical, sectional view through a portion of the silo wall.

Fig. 3 shows a perspective view of a fragment of a silo wall, one course of the wooden boards or strips being spaced above the next lower course to illustrate the manner of assembling the device.

Fig. 4 shows a plan view of one of the boards or strips; and

Fig. 5 shows a similar view of another board or strip.

For the main part of the wall structure of my silo I use two types of strips or boards.

The two types are illustrated in Figs. 4 and 5. One type is used in laying on course and the other type in laying the next adjacent alternate course.

The strip or unit shown in Fig. 4 is indicated by the reference character 10 and is beveled or cut obliquely at its ends and is longer at its inner than at its outer edge as shown.

The angles of the bevels of the ends 11

and 12 depend upon the size of wall which 55 is to be built.

At the one end of each strip or unit 10 adjacent the inner edge thereof is a notch 13, one wall A of which is parallel with the outer and inner edges of the unit, and the other wall B of which is parallel with the beveled end 12.

The unit 10 is provided on its upper surface with spaced longitudinal ribs 14 and 15 which are spaced from the inner and outer edges respectively of the unit, and which extend from the beveled end 11 toward the other end of the unit and extend at said other end beyond the projected line of the edge B.

The ends of the ribs 14 and 15 adjacent to the end 12 of the unit are beveled as at C. The unit 10 is provided near the end 12 and substantially mid-way between its side edges with a vertical hole 16.

The other unit, indicated by the reference character 17, has the beveled ends 18 and 19. At its inner edge and adjacent to the end 18, the unit 17 has a notch 20 similar in general construction to the notch 13, having one wall D parallel with the inner and outer edges of the unit and another wall E parallel with the end 18.

On the upper surfaces of the unit 17 are longitudinal ribs 21 and 22 extending from 85 the end 19 toward the other end of the unit and extending beyond the projected line of the edge E, as shown in Fig. 5. The ends of the ribs 21 and 22 are beveled as at F in a plane parallel with that of the face of 90 the beveled end 18.

Each unit is provided on its under surface with spaced grooves 23 which are slightly deeper and wider than the height of the ribs 14, 15, 21 and 22, as shown in Fig. 2.

In building my improved silo, the foundation 24 is first provided.

The lower course or layer of the units is then laid.

Assuming that in the lower course units 100 10, are employed, the units are laid as shown in the top course in Fig. 3.

The beveled end 11 of one unit is arranged projecting into the notch 13 of the adjacent unit, as shown at the upper part 105 of Fig. 3. The next course is then laid from the unit 17. In each unit 17 near the end 18 is a hole 25. The unit 17 is placed

above one of the units 10, with the end 18 projecting beyond the end 11 of the next lower unit 10, and overlapping the end 12 of one of the lower units 10, in such manner 5 that the holes 25 and 16 register with each other.

The end 19 of each unit 17 is arranged to project into the notch 20 of an adjacent unit 17 in the same course.

10 The end 19 of each unit 17 is arranged flush with the ends C of the ribs of the units 10 of the next lower and upper units 10.

It will be seen that with this construction, each unit 10 is interlocked at its ends with adjacent units 10, and that each unit 17 is interlocked at its ends with adjacent units 17.

15 It will also be observed that each unit 10 overlaps a unit 17 at its end 11 and is overlapped by the unit 17 at the end 12, so that joints are broken in alternate courses.

20 After a few of the units have been laid upright rods 26 are inserted through the holes 16 and 25.

25 Each unit 10 is located on one of the rods at its right-hand end, and each unit 17 is located on one of the rods at its left-hand end.

30 The rods are so arranged as to successively break the joints if more than one rod is used in vertical alinement.

35 The ribs or tongues and grooves are so arranged that the grooves of each upper course receive ribs or tongues of the next lower course.

The parts are so arranged that the edge D of the unit 17 fits against the edges C of the ribs 14 and 15 of the unit 10.

40 In Fig. 3 I have shown the top course slightly raised above the next lower course to better illustrate the parts.

45 It will be noted that when the top course is resting upon the next lower course, the joints between the units 10 will not register with the joints between the units 17.

50 As the courses are laid nails 27 are driven into the units of several courses, as indicated in Fig. 2. The nails are started just outside and inside the respective ribs 14, 15 and 21 and 22, as illustrated, and are inclined downwardly and inwardly, and downwardly and outwardly, respectively, as shown.

55 The outer nails are driven first, and it will be seen that this tends to draw the upper courses inwardly with relation to the lower courses for forcing the units into tight fitting joints. The inner nails may be omitted if desired.

60 At the corners I place upright boards 28 as shown, on the outside of the silo structure. At the inner corners are placed upright wooden members or the like 29 with beveled faces to fit the inner face of the wall.

65 It will be seen that moisture will not travel inwardly or outwardly through the

siloh wall. The corners are protected against such travel of moisture by the members 28 and 29.

70 Between the corners the travel of moisture is prevented by the arrangement of the ribs and grooves.

75 Moisture from the ensilage traveling outwardly between two courses, will not travel through the hollow space between the inner rib and the next unit above.

80 The arrangement of the grooves deeper than the ribs or tongues not only prevents the discharge of moisture inwardly or outwardly through the silo wall, but also provides for expansion and contraction of the units.

85 It will be understood that suitable doors 30 may be provided and that a roof 31 may be placed on the silo in the ordinary way.

90 The advantages of a structure such as 85 that herein described may be largely seen from the foregoing description of my silo.

I have provided an absolutely rigid silo which may be made at relatively small expense.

95 The units may be made of relatively small pieces of lumber which, in many instances, would otherwise be wasted, and can, therefore, be purchased at lower prices.

Each unit is locked to its next adjacent 95 unit and is held in position on the rib 26.

100 The units of one course are locked to the units of the next upper and lower course by the tongue and groove structure, and by the ribs 26.

105 On account of the ribs 26, which are alternately inserted through the units in different courses, the resulting silo structure will be upright and will not twist.

Twisting is also prevented by the structure at the ends of the respective units in the course in their interlocking feature and rods, and by the arrangement of the ribs and grooves.

110 Some changes may be made in the construction and arrangement of the various parts of my improved silo structure without departing from the real spirit and purpose of my invention, and it is my intention to cover by my claim any modified forms of 115 structure or use of mechanical equivalents which may be reasonably included within their scope.

115 I claim as my invention:

120 In a polygonal silo structure, a series of superposed courses, one course comprising a series of units, each having its ends oppositely beveled from the edge of the unit outwardly and toward each other, and having near one end at its inner edge a notch 125 with one wall parallel with the inner and outer edges of the unit, and the other wall parallel with the adjacent beveled edge, said unit having grooves in one side and having ribs on the other side formed with beveled 130

ends parallel with and spaced from the nearest beveled end of the unit, and extending beyond the projected plane of the last-described wall of said notch, each unit of 5 the course having one end received in the notch of the next unit, an alternate course comprising a similar series of units, each having its notch at its opposite end from

that of the first unit, each unit in each course being laid with one wall of its notch 10 abutting against the beveled ends of the ribs of a unit of an alternate course, whereby each unit is locked against movement in every direction.

Des Moines, Iowa, March 22, 1920.
EDWARD STEWART.
